UNITED STATES PATENT OFFICE

103,704

DESIGN FOR A DRESS ORNAMENT

Cornel Balog, New York, N. Y.

Application June 22, 1936, Serial No. 63,428

Term of patent 3½ years

To all whom it may concern:

Be it known that I, Cornel Balog, a citizen of the United States and a resident of the city, county, and State of New York, have invented a new, original, and ornamental Design for a Dress Ornament, of which the following is a specification, reference being had to the accompanying drawing, forming a part thereof, wherein:

Fig. 1 is a front elevational view of a dress ornament showing my new design, and

Fig. 2 is a side elevational view thereof.

I claim:

The ornamental design for a dress ornament substantially as shown.

CORNEL BALOG.
